(57) **CLAIM**

The ornamental design for a wheel carrier bracket assembly as shown and described.

DESCRIPTION

FIG. 1 is a front elevation view of an ornamental design of a wheel carrier bracket assembly;

FIG. 2 is a rear elevation view of the wheel carrier bracket assembly;

FIG. 3 is a top plan view of the wheel carrier bracket assembly;

FIG. 4 is a bottom plan view of the wheel carrier bracket assembly;

FIG. 5 is an elevation view of a first end of the wheel carrier bracket assembly;

FIG. 6 is an elevation view of a second end of the wheel carrier bracket assembly;

FIG. 7 is a front top perspective view from the second end of the wheel carrier bracket assembly; and,

FIG. 8 is a bottom rear perspective view from the first end of the wheel carrier bracket assembly.

The broken lines represent portions of the structure that form no part of the claim.

1 Claim, 6 Drawing Sheets
